 corner A, is one fourth of a figure, having
 eight rounded arms or projections, resting on the ground 1; this ground
 is enclosed by the broad scalloped frame 2, to the outer edge of which is
 attached the lace work 3. The figures of corner B. are similar to those of
 corner A.

In corner C. is one fourth of a set figure resting on the ground

The broad oval frame 6, surrounds the frame 5, and supports four groups consisting of three large bunches and clusters of grapes. Sections of two of the above-mentioned groups are shown at 7. and 8. in the drawing. The figures and surroundings of corner D. are similar to those of corner C. E. in the centre is a plain leaf, resting on a ground surrounded by the branches of leaves 9. and 10. The remainder of the design is occupied by a mottled ground work.
